William Eastburgh
S. Eastburgh
S. Eastburgh

To Schedule, referred to in these Letters Patent and marking Part 2 in Volume
containing a description in the words of the said William Eastburgh, relating
to his improvement in the mode of building Ships.

This patent is a patent and exclusive right given for application of his
said principle, whether Vertically, Horizontally, diagonally applied in the
building or arrangement of the said ship, or parts thereof, material in the
construction or rigging of ships, vessels, & objects of any description; and with
in the rigging of houses, when not made like in all cases; lateral or other
rigging. The annexed plan is a partial illustration of the principle as regards
the lateral rigging of the deck of objects, when rolling or pitching and plainly
manifests that the use of beams and baulks as the marine heretofore used
may be entirely dispensed with and augmented strength acquired and
a diagonal application bringing into use planks of such thickness
would otherwise be required to impart even a new force and strength. The ap-
plication of the same principle may be made highly useful in the rigging
and framing of vessels, and in their external plannings; but particularly in
the rigging or internal planking of each plank only as a brace to every
mold and rib, in a diagonal or angular direction instead of the old her-
etofore used or straight forward manner. The outer deck planks may be made
with fine planks or beams having and grooved and tenon, mortised, with
such configurations to the lower deck and the transom to the fore.

Large vessels, where great strength in the
beam is required, a special and particular advantage is manifest. Both in
the saving of timber and the additional strength acquired by the division of the
beam into two parts; and the more especially as the longitudinal beam to
beam them may by this proper insertion be made to serve as the strength
communicate in the resistance of lateral pressure. The application to the rigging
and lateral the rigging of buildings in masonry made of the least possible
